UNITED STATES PATENT OFFICE.

LOUIS PAUL GUIGNARD, OF FLUNTERN, NEAR ZURICH, AND JAKOB SCHWEIZER, OF UNTERSTRASS, NEAR ZURICH, SWITZERLAND.

APPARATUS FOR BURNING PETROLEUM OR SIMILAR SUBSTANCES.

SPECIFICATION forming part of Letters Patent No. 404,399, dated June 4, 1889.

Application filed August 30, 1888. Serial No. 284,174. (No model.) Patented in France May 4, 1888, No. 190,410, and in England July 24, 1888, No. 10,684.

To all whom it may concern:

Be it known that we, LOUIS PAUL GUIGNARD, a citizen of Switzerland, residing at Fluntern, near Zurich, in Switzerland, and JAKOB SCHWEIZER, a citizen of Switzerland, residing at Unterstrass, near Zurich, in Switzerland, have invented a new and useful Apparatus for Burning Petroleum or other Similar Substances, (for which we have received a patent in France, numbered 190,410, dated May 4, 1888, with additional application dated June 27, 1888, and in England, numbered 10,684, dated July 24, 1888,) of which the following is a specification.

The apparatus, intended for the burning of ordinary petroleum or similar substances, convert the same first into a gas, which, streaming out through a small aperture, mixes with the air, and once lighted continues to burn in a regular manner. The mixture with air takes place in a cylinder in the interior of the burner or retort, so that there is no condensation of the gas, and the mixture being very hot the combustion is complete, and consequently devoid of smoke and smell. The same apparatus may be made to produce either a single "blast-flame" of considerable length or a "silent flame," which is adapted for cooking and heating purposes. The blast-flame may be employed in various industries—such as smelting, welding, soldering, &c.—and may with advantage be used for heating steam-boilers, in which case it of itself produces sufficient draft, rendering the use of long chimneys, steam-blasts, and the like unnecessary. The combustible in the form of a fluid, which is to be burned in a gaseous form, is, as a rule, contained in an air-tight receptacle partially filled with the same. In this, preferably by means of an air-pump, a higher pressure than the atmosphere is produced, under the influence of which the fluid passes from the receptacle through a tube into the apparatus or burner. It is also possible to employ a receptacle placed higher than the apparatus or burner from which the fluid will simply flow downward by gravity through the feed-tube into the evaporating apparatus or burner.

In the accompanying drawings, Figure 1 represents a vertical longitudinal section of

the silent burner; Fig. 2, a cross-section of the silent burner; Fig. 3, a side view of the silent burner; Fig. 4, an end view of the silent burner; Fig. 5, a vertical longitudinal section of the blast-burner. Fig. 6 is a cross-section on the line 6 in Fig. 5. Fig. 7 is an end view of the blast-burner. Fig. 8 is a cross-section on the line 8 in Fig. 5. Fig. 9 is a cross-section on the line 9 in Fig. 5, and Fig. 10 is a side view of the blast-burner. Fig. 11 is a sectional view of the silent burner in activity. Fig. 12 is a side elevation, partly broken, of the silent burner when the gas is burning. Fig. 13 is a similar view to Fig. 12 of a blast-burner in operation. Fig. 14 is a partly broken side elevation showing the burner applied to a cooking-stove, and Fig. 15 shows the silent burner as applied to a boiler.

The apparatus or burner consists of a metal cylinder *a*, Figs. 1 and 5, having a series of external annular flanges, which flanges have recesses *c'* or openings. The cylinder *a* is inclosed by a metal jacket *b*. The chamber or space *c* between cylinder and jacket is closed at both ends by end flanges, (these being without the recesses *c'* on the cylinder *a*,) the cylinder and jacket being soldered together. The chamber or space *c* is completely isolated from the outer air. The recesses *c'* in the flanges on the cylinder form passages for the fluid and gas between the cylinder *a* and jacket *b* from chamber to chamber. The apparatus or burner forms a sort of retort into which the feed-tube *d* leads. The fluid passes through the tube *d* into the chamber or space *c* between the cylinder *a* and jacket *b*.

The combustible fluid passing into the apparatus is evaporated in proportion to the consumption and issues into the cylinder in the form of gas in an axial direction through a small tube or jet *e* situated in the cylinder-axis at one end of the cylinder and communicating with the space *c*. The cup *h*, Figs. 5 to 10, in the fixed tube *d* is to be filled with spirits for heating the apparatus or burner when starting it. When so heated, the fluid in the chamber or space *c* will be converted into gas, which will pass from the chamber or space *c* through the jet *e* into the cylinder *a*. The

pressure under which the gas issues gives the same a considerable rapidity. Gases containing a larger amount of pure oxygen could also be employed when great heat is required.

5 When the gas is lighted, a long blast-flame is formed, which appears at the open end of the cylinder. This flame keeps the apparatus hot, thereby generating more gas as it is consumed. The plug *i* will be removed when the jet *e* is 10 to be cleaned. When a silent burner is desired, the above-described apparatus is simply covered by a second cylindrical jacket *f* at a small distance from the first. This exterior jacket *f*, Fig. 1, is pierced in a sieve-like manner by a number of small holes *g g*, Fig. 3, or apertures of any form. It is closed at the end opposite the gas-jet and secured to a flange on the jacket *b* at the jet end of the burner. The stream of gas issues in the same way as 15 before from the cylinder. It strikes against the covering of the outer jacket and is blown and whirled back into the space between the inner and outer jackets *b* and *f*, from whence it issues into the open air through the apertures *g*, at which it is ignited. For special 20 purposes the apertures may be placed either over the whole surface or on any single part of it. The flames surrounding the outer jacket maintain the whole apparatus at a 25 sufficiently high temperature to effect the evaporation of the combustible fluid, the flow of which is in both cases regulated by suitable means applied to the feed-pipe.

For the silent apparatus the cylindrical outer jacket could be replaced by a jacket of 30 different shape from that shown to suit the form desired for the burner. The object to be attained by this combination is, first, to prevent the mixture of petroleum-gas and 35 air from taking fire on issuing from the cylinder, and, secondly, to conduct this mixture into a place adapted to the employment of the burner, from which it finds exit into the open air by the above-mentioned apertures, 40 at which it is ignited. This space must be proportioned in such a way that part of the heat produced maintains the retort at a suf-

ficiently high temperature for the regular evaporation. If desired, the first jacket may also receive a somewhat altered form.

50

In Fig. 11 is shown a silent burner, wherein the different changes in the condition of the petroleum are shown, from its entering the burner by the tube *d* until it is ready to leave the burner to be ignited. In Fig. 15 the silent burner is applied to heat water in the boiler B. In order to get a soft-blast flame the burner is provided with holes *g* at one end for the passage of the combustible. The burner is shown within a heating-tube T of the 60 boiler B.

55

Having now particularly described and ascertained the nature of oursaid invention and in what manner the same is to be performed, we declare that what we claim is—

65

1. The combination of the cylinder *a*, having external annular flanges and provided with recesses *c'* in each of said flanges, jacket *b* resting on said flanges, forming chambers or spaces *c* between the cylinder and jacket, 70 the chambers or spaces *c* communicating through the recesses *c'* with each other and with the feed-tube *d*, leading to one of the chambers or spaces *c*, and the jet *e*, leading from one of the chambers or spaces *c* to the 75 interior of the cylinder *a*, substantially as described.

2. The combination of the cylinder *a* and jacket *b* around said cylinder, forming the chamber or space *c* between said cylinder and 80 jacket, with the outer apertured jacket *f*, feed-tube *d*, leading to the chamber or space *c*, and jet *e*, leading from the chamber or space *c* to the interior of the cylinder *a*, substantially as described.

85

In testimony whereof we sign this specification in the presence of two subscribing witnesses.

LOUIS PAUL GUIGNARD.
JAKOB SCHWEIZER.
